UNITED STATES PATENT OFFICE.

JOHN MEISSNER, OF NEW YORK, N. Y., ASSIGNOR TO HIMSELF, REQUIA FLEISCHMAN, ISAAC KAYSER, PHILIP L. SONDHEIM, LOUIS STECKLER, AND JOHN C. STANTON, JR., ALL OF SAME PLACE.

CAR-BRAKE.

SPECIFICATION forming part of Letters Patent No. 328,959, dated October 27, 1885.

Application filed November 25, 1884. Serial No. 148,805. (No model.)

To all whom it may concern:

Be it known that I, JOHN MEISSNER, of the city, county, and State of New York, have invented a certain new and useful Improvement 5 in Car-Brakes, of which I declare the following to be a full, clear, and exact description, so that any one skilled in the art to which it appertains may make, construct, and use the same, reference being had to the accompanying 10 drawings, which form part of this specification, and to the letters and figures of reference thereon.

My invention relates to improvements in car-brakes, and has for its object to provide 15 brakes simple in construction and capable of being easily and effectively applied.

Figure 1 is a sectional side view with part of the truck frame and supports removed. Fig. 2 is a top view of a truck, and Fig. 3 an 20 end view.

Like letters refer to corresponding parts in the different figures.

The cross-pieces H H h h constitute the 25 movable brake-frame. To this are fastened brake-rods S, each of which carries at its ends the brake-shoes M M'. These brake-shoes are curved to conform somewhat to the periphery of the wheel, and may, as shown in the drawings, be detachably secured to the brake-rod, 30 to enable them to be replaced when worn out. I prefer to make these shoes of metal. They may, however, be made of any suitable material.

Secured to the truck-frame is a bent rod, L, around which are fastened two bearings, N N, 35 through which, and immediately beneath the rod L, passes the brake-rod S. The bearings N N allow this brake-rod S to move longitudinally along and under the rod L; but they and the rod L prevent it from moving vertically 40 or laterally.

The lever B is fastened to the shaft of the 45 brake-wheel A and turns with it, and at its other end is pivoted to the rod C, which is in turn pivoted at its other end to the lever D. This lever is pivoted to the truck-frame at d. Near its center one end of the arm E is pivoted, the other end being pivoted to the movable frame H.

The operation of my device is as follows: If the car is moving in the direction indicated by the arrow x, Fig. 1, the brake-wheel is turned in the direction of the arrow y, as shown in Fig. 2, taking with it the lever B, and transmitting the forward motion through C, D, and E to the movable brake-frame. The latter carries forward with it the brake-rod S and the 50 brake-shoes, thereby pressing the brake shoes M against the wheel. The moment the brake-shoe M touches the moving wheel, which is revolving in the direction indicated by the arrow z, Fig. 1, the upward and forward motion of the periphery of the wheel tends to carry the brake-shoe M along with it, and thereby wedges the brake-shoe M and the brake-rod S 55 between the wheel and the rod L. It is evident that the force with which this wedging is done will vary with the varying velocity of revolution of the wheel. The more rapid the revolutions the greater will be the wedging force and the more effective will the brakes become. 60 As this does not depend upon the force exerted at the brake-wheel A, very little power is needed in applying the brakes, my device utilizing the speed and momentum of the car to stop the car. If the car is moving in the contrary direction, the brake-wheel is turned in the reverse direction to that indicated by the arrow y. In this case the brake-shoes M' are 65 used.

My device does not jar or interfere with the 70 easy riding of the car, because of the firm grasp and uniform operation of the brakes, and because it admits of the insertion in the line of load of the ordinary or any car springs.

The movable brake-frame imparts motion to 75 all the brake-rods of the truck simultaneously. The bar i carries this motion to the other truck of the car, the bar K connecting with a similar bar from another car, and so on from car to car, allows the brakes throughout an entire 80 train to be operated and controlled from the engine. A short steam-cylinder and piston-rod could thus be made to operate all the brakes in a train.

The form of the movable brake-frame and 85 the means of imparting longitudinal motion

thereto might be varied, if desired, without departing from the spirit of my invention, and the brake-rod S might be dispensed with, each brake-shoe being directly connected with the movable brake-frame, in which case it would be necessary for a fixed part of or projection from the truck to lie or project over each brake-shoe, between which and the wheel the brake-shoe could be wedged, as before described.

My invention furnishes a simple, cheap, and effective brake, which can be easily applied, and which does not interfere with the easy riding of the car.

What I claim as new, and desire to secure by Letters Patent, is—

1. The combination, with a truck, of a movable brake-frame, brake-shoes, and a fixed part of or projection from said truck lying over said brake-shoes, whereby the brake-shoes may be wedged between the wheel and the fixed part of or projection from the truck lying over the brake-shoes, substantially as and for the purposes set forth.
2. The combination, with a truck, of a movable brake-frame, brake-shoes, and connecting brake-rod, all so arranged that the brake-

shoes and connecting brake-rod may be wedged between the wheel and a fixed part of or projection from the truck, substantially as and for the purposes set forth.

3. In a car-brake, the combination of a movable brake-frame, brake-shoes M M', brake-rod S, rod L, and bearings N N, substantially as shown and described.

4. In a car-brake, the combination of a movable brake-frame, lever B, arm C, lever D, arm E, rod L, bearings N N, brake-rod S, and brake-shoes M M', substantially as and for the purposes set forth.

5. The combination, with a movable brake-frame, brake-shoes M M', connected by brake-rod S, rod L, and bearings N N, of arms K and i, substantially as and for the purposes set forth.

6. The combination, in a car-brake, of a movable brake-frame, lever B, arm C, lever D, arm E, brake-shoes M M', brake-rod S, rod L, bearings N, and rods K and i, substantially as and for the purposes set forth.

JOHN MEISSNER.
